[57] CLAIM

The ornamental design for a combined plate and cup carrier, as shown and described.

DESCRIPTION

FIG. 1 is an isometric view of the combined plate and cup carrier, showing my new design;
FIG. 2 is a top plan view thereof;
FIG. 3 is a front elevational view thereof, the rear elevational view being a mirror image of FIG. 3;
FIG. 4 is a left side elevational view thereof;
FIG. 5 is a right side elevational view thereof; and,
FIG. 6 is a bottom view thereof.

FIG.1**FIG.2****FIG.3**

FIG.4**FIG.5****FIG.6**
